C. D. Stackins

UNITED STATES PATENT OFFICE.

JOSEPH F. DWYER, OF SEATTLE, WASHINGTON.

DEVICE FOR DISPENSING TICKETS.

1,268,222.

Specification of Letters Patent. Patented June 4, 1918.

Application filed January 28, 1918. Serial No. 214,182.

To all whom it may concern:

Be it known that I, JOSEPH F. DWYER, citizen of the United States, residing at Seattle, in the county of King and State of Washington, have invented a certain new and useful Improvement in Devices for Dispensing Tickets, of which the following is a specification.

My invention relates to improvements in devices for dispensing tickets from ticket rolls and the object of my invention is to provide a simple and efficient device of this nature that will place the end ticket on the roll within easy access of a purchaser and in a position where it is protected but may be easily seen and read before it is purchased.

A further object of my invention is to provide a device of this class consisting of a receptacle or box into which a plurality of ticket rolls may be easily and quickly inserted and to provide suitable means, in the form of a removable side for the box having rigid spaced apart partitions, for separating the several rolls from each other and for holding the rolls in the correct alinement with slots through which the tickets are dispensed.

A still further object is to provide a tension device that will permit the tickets to be freely removed but will prevent them from being pushed back into the box after they have been partially drawn.

The invention consists in the novel construction, adaptation and combination of parts as will be more clearly hereinafter described and claimed.

The device is particularly well adapted for dispensing tickets from ticket rolls in such manner that the ticket on the outer end of the roll will always be visible and that none of the other tickets on the roll will be visible as the tickets are successively torn off and is intended for dispensing tickets from rolls wherein each ticket specifies a small article of merchandise that is being sold to the purchaser and a few of the tickets specify a valuable article of merchandise that is sold along with the smaller article.

I accomplish these objects by devices illustrated in the accompanying drawings, wherein—

Figure 1 is a view in perspective of a device constructed in accordance with my invention;

Fig. 2 is a view in cross-section substantially on broken line 2, 2 of Fig. 1;

Fig. 3 is a view in cross-section on broken line 3, 3 of Fig. 2;

Fig. 4 is a fragmentary view in perspective illustrating a detail of the invention; and

Fig. 5 is a plan view illustrating one form of tickets that may be dispensed by this device.

Referring to the drawings, throughout which like reference numerals designate like parts, the numeral 6 indicates the bottom of a box that is provided with two end walls 7 and 8, a top 9 and front and rear side walls 10 and 11 respectively, the rear side wall 11 being in the form of a removable door.

The front side wall 10 is provided at a short distance from the top with an inclined shelf that is formed with a plurality of ticket grooves 12 that are spaced from each other by ribs 13 and communicate at their upper ends with the interior of the box by slots 14.

The grooves 12 are each wide enough for the reception of tickets that are in the well known form of a strip or ribbon 15 of heavy paper or cardboard that may be rolled and placed on a spindle or shaft 16 that extends lengthwise within the box and has its ends supported within slots 17 in the opposite end walls 7 and 8 of the box.

The slots 17 extend to the rear side of the box so that the shaft 16 may easily be inserted or removed therefrom.

The back wall 11 of the box is removable and is provided with a plurality of rigid partitions or spacing members 18 that fit between adjacent rolls of tickets 15 on the shaft 16 and to keep the several rolls in the correct alinement with their respective ticket outlet openings and to prevent the rolls from rubbing against and tending to unwind each other.

The partitions 18 are each provided with slots 20 on the front edge that fit over the shaft 16 and coöperate with the slots 17 in the end walls to form a support for the shaft 16 and prevent it from being moved rearward in the box.

The ribs 13 are adapted to have a transparent plate 21 rest thereon and cover the grooves 12, the plate 21 being secured to the box by overlapping cleats 22 disposed at each end thereof.

The grooves 12 are just wide enough to

permit the passage of the ticket strips 15 and the front side of the box is recessed as at 23 adjacent the outer end of each of said grooves so that a person can reach the fingers 5 into the recesses 23 and get hold of the tickets to pull them out.

The ticket strips 15 are perforated at intervals in a well known manner as indicated at 24 so that they will tear easily and 10 at right angles to the strip.

The ticket rolls are placed on the shaft 16 so that the strips 15 may be passed upwardly from the front side of the rolls around a fixed guide 25, between such guide 15 and tension members 26 and thence outwardly through the slots 14 and grooves 12.

The tension members 26 are mounted on a transverse shaft or pin 27 and are held in engagement with the ticket strip by a 20 spring 28, the arrangement of the tension members being such that they normally exert a yielding pressure on the ticket strips 15 and permit them to be drawn out of the box but will forcibly wedge the 25 ticket strips 15 between themselves and the guide 25 and will prevent the ticket strips from being pushed back into the box after they have been drawn out of the box far enough to be read.

20 The lowermost front edge of the transparent plate 21 is preferably straight and sharp so that it will facilitate the tearing off of the tickets.

The tickets may have printed matter on 25 one side to indicate the nature of the purchase that is made and this printed matter is clearly visible at all times through the transparent plate 21.

The tickets are preferably printed and rolled and may have their ends inserted between the guide 25 and friction members 26 and projected into the grooves 12 so that the first ticket on the roll may be read through the transparent plate 21.

The rolls are then placed on the shaft 16 in their proper order, the shaft is inserted in the slots 17 and the back wall 11 with its partition members 18 is brought into place to close the box and hold the ticket rolls in the proper spaced relation.

The tickets may be printed in various ways to indicate the merchandise that they represent and occasionally one of such tickets may indicate that the purchaser gets, not only the usual small article of merchandise, but also gets a valuable article, as a camera or the like along with it. Thus a person is aware of the article he is buying when he pulls out a ticket but he does

not know what is on the next ticket adjacent to the one displayed until he pulls out the displayed ticket and brings the one next adjacent into view through the transparent plate 21. If when he pulls a ticket he brings into view another ticket conveying 65 the right to a valuable article it is obvious that he can buy this ticket and can pull the same and claim the valuable article.

It is obvious that this device may be made to handle any desired number of ticket rolls 70 and that changes may be resorted to within the scope of the following claims.

What I claim is:

1. A device for dispensing tickets from a ticket roll comprising a receptacle having 75 grooves through which the tickets may be withdrawn, said receptacle being provided in each end wall with slots that extend from the rear side thereof forwardly; a shaft whereon ticket rolls may be placed, 80 said shaft being adapted to be inserted in said slots; a removable back wall for said receptacle and guide members fixedly secured to said removable back wall adapted to be inserted between the ticket rolls on 85 said shaft to hold said ticket rolls in spaced apart relation said guide members having slots that fit over said shaft and coöperate with said slots in the end walls of said receptacle to form a support for said shaft. 90

2. A ticket dispenser comprising a rectangular boxlike receptacle, an inclined shelf formed on the front side of said receptacle and provided with ticket receiving grooves that are separated from each other 95 by ribs and communicate with the interior of said receptacle by means of slots formed at the ends of said grooves; a transparent plate adapted to rest on said ribs and cover said grooves whereby the tickets in said 100 grooves will be visible; a shaft supported transversely of said receptacle and adapted to have ticket rolls placed thereon; a removable side provided in said receptacle; guide members carried by said removable 105 side and adapted to be inserted between said rolls to hold said rolls in spaced apart relation; a guide over which the tickets may pass from said roll to said grooves; and tension devices engaging said tickets, the said 110 tension devices permitting said tickets to be withdrawn from said receptacle but preventing said tickets from being pushed back into said receptacle.

In witness whereof, I hereunto subscribe 115 my name this 21st day of January, A. D. 1918.

JOSEPH F. DWYER.
